ROAD SEMI-SURFACING IMPLEMENT

Oliver A. Rich, Bakersfield, Calif., assignor of
one-half to United Patents Inc., Modesto, Calif.,
a corporation of California

Application July 26, 1935, Serial No. 33,219

5 Claims. (Cl. 94—44)

This invention relates to road surfacing equipment and is directed particularly to an implement for forming what is termed a "semi-surface" on a road.

5 In many instances where the travel over a road is relatively heavy but not sufficient to warrant the expense of paving the road with concrete or macadam, the road is surfaced with a mixture of crude oil and earth which, when spread over the 10 road bed and rolled forms a very satisfactory surface. This is known as semi-surfacing and although it must be replaced every few years, it is much less expensive than true paving and prevents the road from being exceedingly dusty in 15 summer while preventing the winter quagmire of totally unsurfaced roads.

In putting down a semi-surface however certain difficulties have arisen, especially in regard to the manner in which the oil and earth were 20 mixed and spread over the road bed. It has been accomplished by first scraping the earth from the surface of the road bed into a ridge along the road and then spraying the oil over the earth ridge, and then scraping the mixture back onto 25 the road bed and subsequently rolling the same. In many instances this method of forming the oiled surface failed to completely mix the oil and earth which resulted in many surface failures causing bad spots in the road which had to be 30 repaired. Further, this method required that the scraper go over the same portion of the road several times and that a separate piece of equipment had to be employed to spread the oil. This method was therefore not only more expensive 35 than necessary but it required too much time in which to apply a semi-surface to a road. Of course, in order not to delay travel over a road, only one-half of the road was surfaced at a time.

It is therefore my principal object to provide 40 an implement which will of itself completely form a semi-surface on a road with a single passage of the implement over any given portion of the road. On relatively narrow roads, the implement may completely surface the entire width of the road as 45 it passes while on relatively wide roads only one-half of the road will be surfaced at a time. However whatever width the implement is adapted to surface, the semi-surface over that width is accomplished rapidly with a single passage of the 50 implement.

A further object of my invention is to provide an implement which will completely mix the loosened earth and oil preparatory to spreading the same 55 over the road bed.

An additional object is to provide a road semi-

surfacing implement which is adjustable in order that the semi-surface applied to the road bed may be of a predetermined and desired thickness. This is an extremely advantageous feature due to the fact that the thickness of the semi-surface depends entirely on the firmness of the road bed and the amount of travel to which the road is to be subjected.

A further object of the invention is to produce a simple and inexpensive device and yet one which 10 will be exceedingly effective for the purpose for which it is designed.

These objects I accomplish by means of such structure and relative arrangement of parts as will fully appear by a perusal of the following 15 specification and claims.

In the drawings similar characters of reference indicate corresponding parts in the several views:

Figure 1 is a side elevation of the machine as in 20 operation.

Figure 2 is a top plan view of the same with the engine and its supporting frame removed.

Figure 3 is a fragmentary enlarged longitudinal 25 section of the machine on the line 3—3 of Figure 2.

Figures 4 and 5 are fragmentary transverse sections of the machine taken on the lines 4—4 and 5—5 respectively of Figure 2.

Figure 6 is a fragmentary section on the line 30 6—6 of Figure 2.

Referring now more particularly to the characters of reference on the drawings, the machine comprises a rectangular horizontal supporting frame 1 having a clevice 2 or the like at its forward end whereby it may be connected in trailing relation to an oil tank truck 3.

The frame is supported at the front end by 40 castor wheels 4 and at its rear end by larger and relatively fixed wheels 5; all the wheels being outwardly of the frame. The supporting forks 6 of the castor wheels swivelly depend from arms 7 which extend forwardly from a cross shaft 8 journaled on the frame 1. The rear shaft 8 is journaled on the frame 1. The rear wheels are supported from arms 9 which project 45 rearwardly from a cross shaft 10 journaled on the frame 1.

The wheels are raised and lowered by suitable means, preferably in such a manner that the rear wheels when being lowered (to correspondingly raise the frame) will be moved a certain amount before any movement is imparted to the front wheels. This may be accomplished by various types of mechanisms. In the present instance I 55 have shown the wheel controlling mechanism as

comprising a hydraulic cylinder 11 extending lengthwise of the frame 1 and immovably mounted thereon in any suitable manner. The piston rod 12 from the piston 13 of the cylinder 5 projects from both ends of the cylinder. At its rear end this rod is operatively connected to an arm 14 fixed on and upstanding from the shaft 10. At its forward end the rod 12 is connected to a cross pin 15 which slides in slotted 10 links 16 projecting rearwardly from an arm 17 fixed on and upstanding from the shaft 8.

When the forward end of the frame is in its lowest position, adjustable stops 18 mounted in stop arms 18a on the shaft 8 engage the front 15 cross bar of the frame 1 and prevent turning of the shaft 8 in a direction to relatively raise the front wheels 4. When the rear wheels 5 are raised relative to the frame, the piston 13 is adjacent the forward end of the cylinder 11 and the pin 15 20 is adjacent the forward end of the link slots. With the rearward movement of the piston rod 12 a relative lowering of the rear wheels immediately takes place. No corresponding movement is imparted to the front wheels however until the pin 15 engages the rear end of the link slots 25 and exerts a pull on the links and the arm 17 to turn the shaft 8 in a wheel lowering direction. The purpose of this particular arrangement will be seen later.

30 The control of the hydraulic fluid to either end of the cylinder selectively is of course accomplished by a suitable piping and control valve arrangement V from a source of fluid pressure; and since such equipment is common to all hydraulic apparatus and forms no part of my invention, it is not deemed necessary to illustrate or describe the same.

35 Journaled in boxes 19 secured to the sides of the frame 1 in depending relation thereto are the scarifier units, any suitable number of these rolls being used. These units extend the full distance between continuous skirt plates 20 secured to and depending from the inner faces of the sides of the frame 1, and are set in spaced 40 relation lengthwise of the frame. Each unit is disposed on a level somewhat lower than the adjacent one in front so that said units as a whole are set with a downward slope from front to rear. Each unit comprises a shaft or central 45 portion 21 having a spiral material cutting or scarifying blade 22 thereon, so that the units are in effect combination cutting augers, and conveyors, tending to cause the scarified material to travel toward one end of the rolls.

50 The blades 22 are disposed with alternately right and left hand pitch on the successive shafts, though they are all driven in the same forward direction. Such driving may be accomplished by suitable means, such as chain and 55 socket units 23 connecting the various axial shafts 21 of the units at one end thereof and outwardly of the bearing boxes 19. One of said shafts is driven by suitable means 24 and at a reduced speed from a power plant such as a gas 60 engine 25 supported from the frame 1 above the rolls. It is to be understood that a change speed transmission is included in the drive connection between the engine and said shaft so that the speed of the units may be altered while maintaining the engine speed constant and as operating 65 conditions may require.

60 Secured to and depending immediately behind the different units and extending the full length and to the level of the bottom thereof are vertical 70 baffle plates 26, each having at one end only a

relatively large opening 27 cut upwardly from the bottom and disposed at that end of the corresponding unit toward which the material will be moved by the rotation of said unit.

It will therefore be seen that with the rotation 5 of the units and the advancing movement of said units along the ground as the machine advances, the material will be engaged and scarified to successively greater depths, and such material as loosened will be banked up against the corresponding baffle plates and fed toward one end 10 of the units and plates. Since the units feed the material in alternately different directions on account of the alternately reversed pitch of the spiral blades 22, such material after arriving at 15 and passing through the opening 27 of one baffle plate will become immediately engaged with the adjacent end of the succeeding unit. This material is then mixed with that being scarified and loosened by such succeeding unit and all this material will be conveyed toward the open end of 20 said unit where it passes through the corresponding opening 27. This mixing and moving of the material back and forth continues, the volume of 25 the material increasing of course at each unit, until all the material passes out through the opening 27 in the rearmost plate 26.

The material is then engaged and smoothed 30 out by a leveler blade 28 extending the full width of the units and disposed with its forward edge 35 at a transverse slant away from the adjacent opening 27. This blade is disposed at or adjacent the finished ground level and is provided with vertically slotted uprights 29 at its sides which engage and are secured to the side members of 40 the frame 1 for vertical sliding movement as shown in Figure 6, so that the level of the blade may be adjusted to suit. Such adjustment may be effected by any of the mechanisms commonly employed to adjust leveler blades.

45 In connection with the scarifying and mixing of the material in the manner above described oil is discharged onto the same so as to be mixed with the same in the following manner:

Leading from the tank truck 3 is an oil pipe 30, 45 which includes a flexible detachable section 30a adjacent the truck so that connection may be readily made with different trucks. In operation each truck is filled with oil heated at a central heating plant, and when such truck is empty the 50 pipe section 30a is disconnected, the empty truck detached from the machine and another truck having a fresh supply of hot oil connected to the machine with practically no delay. The pipe 30 is connected to the intake of a pressure pump 55 31 of suitable character driven by the engine 25. From the discharge side of the pump another pipe 32 leads to branch pipes 33 which extend over the scarifying units adjacent their ends and have nozzles 34 depending just back of the various 60 openings 27, so as to discharge onto the materials passing through said openings. The main volume of oil as fed from the pump is controlled by a suitable valve 35 in the pipe 32; there being a by-pass 36 from the pipe 32 ahead of the valve to 65 the intake side of the pump. Also individual valves 37 may be provided for the different nozzles to separately control the flow therethrough.

70 It will therefore be seen that an efficient scarifying and oil mixing action is had with one operation of the machine, and the materials are left behind the machine in a smooth condition ready for final rolling. Raising of the rear end of the frame a greater extent than the front end is necessitated by the fact that the rearmost scari- 75

fying units depend to a depth below the normal surface of the ground a greater distance than the front unit. A relatively great raising of the rear end of the frame is therefore required to clear 5 the rear units for transportation, while at the same time only a slight raising of the front end of the frame is necessary or desired, in order not to unduly disturb the level of the connection of the machine with the truck ahead.

10 By manipulating the adjustable front wheel stops 18, the depth of cut of the front scarifying unit may be altered to suit different conditions.

From the foregoing description it will be readily seen that I have produced such a device as substantially fulfills the objects of the invention as 15 set forth herein.

While this specification sets forth in detail the present and preferred construction of the device, still in practice such deviations from such detail 20 may be resorted to as do not form a departure from the spirit of the invention, as defined by the appended claims.

Having thus described my invention, what I claim as new and useful and desire to secure by 25 Letters Patent is:

1. A road working implement comprising a wheel supported frame adapted to be pulled along the ground, a plurality of longitudinally spaced transversely extending shafts turnably mounted 30 on the frame, power means to drive the shafts all in the same direction, spiral blades projecting outwardly from and extending along the shafts and disposed in alternating right and left hand pitch relation on the different shafts, whereby the 35 material as scarified will tend to be moved toward one end of the shafts, and plates mounted on the frame and depending adjacent and behind the various shafts to a level adjacent that of the

bottom of the corresponding blades, said plates each having a material discharge opening projecting upwardly from the bottom at said one end of the corresponding shaft.

2. A structure as in claim 1, with means to discharge oil onto the material as it passes through the different plate openings. 5

3. A structure as in claim 1, with means mounted on the frame behind the rearmost shaft and plate to engage, level off, and transversely distribute the material discharged through the rearmost plate opening. 10

4. A structure as in claim 1, with a leveling blade mounted on the frame behind the rearmost plate; the forward edge of said blade having a 15 transverse slope to the rear from the end thereof on the same side of the implement as the rearmost plate opening.

5. A road working implement comprising a wheel supported frame adapted to be pulled along the ground, a plurality of longitudinally spaced transverse shafts turnably mounted on the frame, power means to drive said shafts, scarifying units on the shafts arranged relative to the direction 20 of rotation thereof to cause the material as scarified to be moved toward one side of the implement by the scarifying unit of one shaft and toward the opposite side of the implement by the units of adjacent shafts, and members mounted 25 on the machine and extending along and between the various shafts and scarifying units to temporarily confine the material as scarified in the form of transversely extending rows; there being discharge openings in said members at the end 30 thereof toward which the material is being moved 35 by the corresponding scarifying units.

OLIVER A. RICH.
